UNITED STATES PATENT OFFICE.

ALFRED BUTTERWORTH CLEWORTH, OF HOLLINWOOD, ENGLAND.

WET FILTER, WATER-COOLER, HUMIDIFYING APPARATUS, AND THE LIKE.

1,345,131.

Specification of Letters Patent. Patented June 29, 1920.

Application filed January 4, 1918. Serial No. 210,322.

To all whom it may concern:

Be it known that I, ALFRED BUTTERWORTH CLEWORTH, a subject of the King of Great Britain, residing in Hollinwood, England, 5 have invented certain new and useful Improvements in Wet Filters, Water-Coolers, Humidifying Apparatus, and the like, of which the following is a specification.

My invention relates to apparatus for 10 heating, cooling, moistening, cleansing or otherwise treating air or gas with liquid or for cooling water, oil, or other liquid with air, of the type comprising a closed chamber containing the liquid and a horizontal shaft 15 carrying one or more wheel-like bodies or members which consist each of a single disk or a series of disks spaced apart and connected together and are adapted to rotate about the axis of the shaft each with its 20 lower portion immersed in the liquid contained in or passing through the chamber, the said members being provided with a large number of openings or passages through which a current of air or gas entering 25 the chamber at one end is forced or drawn toward an outlet in the chamber, the openings breaking up the body of the air or gas into a number of streams or jets.

My invention consists in an improved construction of disks for use in apparatus of the above kind, the object being to produce a simple and a highly effective plant, which can be readily and cheaply constructed.

Hitherto in apparatus of the character referred to, the disks, constituting the wheel-like bodies or members have been of an openwork nature, being formed of wooden or metal perforated plates or grids, of wire gauze or of textile fabric, but, according to 35 this invention, I make the disks of expanded metal sheets in which the strips of metal between the openings therein are inclined to the faces of the sheets. By so doing, not only is a saving effected in the amount of 40 metal required to provide a strong and reliable disk and the proportion of the passageway area to the total face area of a disk increased, but the oblique passageways of expanded metal offer less resistance to the 45 entry and passage through them of the streams of air or gas. Moreover, the surfaces of the walls or sides of the passages are constituted by portions of the two faces or sides of a disk, so that air or gas passing 50 through the passage is scrubbed against both faces of the disk, whereas in other forms of

openwork material only one side of a disk has been effective. If in a set or nest of expanded metal disks, the adjacent members be arranged so that the openings in them 60 slant in reverse directions, the streams of air or gas in passing from one disk to another are caused to alter their course each time.

The expanded metal disks may be protected in any suitable known manner from the action of gases, as for instance by a coating of earthenware, enamel, cement, asbestos and like substance.

I have found that the use of expanded 70 metal for a disk enables satisfactory results to be obtained with only a very small quantity of water or liquid in the lower part of the apparatus, the marginal or peripheral portions only of the disk passing through 75 the liquid. The whole of the disk while rotated is kept thoroughly wet owing to the liquid taken up by the marginal or edge portions of the disk flowing or dropping toward the center during each revolution, and also 80 owing to the fact that the air carries drops of liquid from one disk to the next disk.

I preferably support or strengthen the material of the disks by means of a frame although in some cases this may not be 85 necessary.

When a wheel-like member comprises a series or sets of disks, the latter, which may be of any desired number, are disposed one behind the other at suitable distances apart 90 along the shaft by or on which they are rotated. Preferably and where possible the openings in the disks are arranged so that those in one disk are staggered with relation to those in an adjacent disk.

The disks may be of complete circular or annular form or may be made in halves or segments so that they may readily be secured on the shaft without having to be threaded thereon and may be also readily 100 disassembled for cleansing or renewal. The disks may be rotated at any desired speed and according to circumstances in each particular case.

Apparatus designed particularly for the 105 cooling of water or other liquid or for cooling air or other gas would preferably have the wheel members arranged in groups and the lower portion of the chamber containing the water or other liquid would be 110 divided into compartments in such a way that the liquid is caused to pass through

each compartment successively and in any desired directions but preferably in counter-current to the flow of air, the air, gas or liquid as the case may be becoming cooler 5 as it passes from one end to the other of the apparatus.

The groups of wheel-members or disks may be rotated all in the same direction and at any desired speed. Alternatively, individual disks or sets of disks constituting the groups may be arranged to run in clockwise and anti-clockwise directions alternately, thus increasing the amount of contact between the air passing through the 15 apparatus with the drops of water formed.

Where the apparatus is used for a wet filter for electric generators or the like, and under all conditions where it is necessary to extract loose drops of liquid from the air 20 leaving the machine, suitable devices for eliminating drops of liquid from the air passing through the apparatus would be provided at the air outlet end of the apparatus. These may be of any known type 25 and may for instance comprise a series of baffle plates consisting of strips of metal bent at a suitable angle or the like fitted into one another across the machine in such a way that the air is caused to take a tortuous course in passing through them and any drops of liquid are deposited on the 30 eliminator and drain back into the lower portion of the machine. These eliminators may be stationary or revolving.

35 The invention will be now further described with reference to the accompanying diagrammatic drawing, in which—

Figure 1 is a longitudinal section of an apparatus having wheel-like members constructed according to the invention, a fan 40 machine for generating an air current being shown diagrammatically in elevation at A.

Fig. 2 is a transverse section of the apparatus shown in Fig. 1.

Fig. 3 is an elevational view of a portion of a disk composed of a number of sector shape segments of expanded metal.

In Figs. 1 and 2, *a* denotes the closed 50 chamber in which the wheel-members rotate with their lower portions immersed in liquid *g*. In Fig. 1 the chamber contains three wheel-members each comprising four disks *b*, but the number of disks may be 55 varied to suit requirements. The disks are here represented as made of expanded metal, and may be connected together at their rims in any suitable manner, for instance a spacing device, consisting of a metal ring *b'* welded to the outer peripheral margin of a disk and a spacing block *b''*, is inserted between each pair of disks, and pins *c* are passed through holes provided in the spacing devices and secured by having their ends riveted over or by means of nuts. The

inner peripheral edges of the disks may be clamped between collars or hubs *d* that fixedly encircle the shaft *e*. This shaft is supported in bearings *e'* and is adapted to be rotated in any convenient manner, as for 70 example by means of the wheel or pulley *f*. In some forms of the improved apparatus it may be advantageous to arrange for the current of air, gas or liquid passing through the apparatus to be used to rotate the wheel- 75 members by suitable mechanical means.

Air is forced or drawn by means of the power actuated fan *A* into the chamber *a* through the terminal louver-like or skewed opening *a'* and flows through the openings 80 in the disks *b* toward the outlet *a''*; a flow of air around the periphery of the disks is checked by the annular-like baffle plates or flanges *a'''*. Adjacent to the outlet *a''* an eliminating device, if used, would be arranged. In Fig. 1 an eliminating device is shown at *h*.

In Fig. 1, the liquid *g* extends throughout the lower part of chamber *a*, but if desired this lower part can be divided into 90 compartments for the purpose stated by arranging therein transverse baffle plates which would be formed and disposed in a manner to cause the liquid in passing from the inlet *p* to the outlet *q* of the chamber 95 to take any desired course. Two such baffle plates are indicated, by way of example, in broken lines at *o* in Fig. 1.

The disks may be each a complete annulus, or may be formed of segmental shape pieces 100 which would be connected together, as for instance by attaching them to arms *i* provided for the purpose and extending radially from the above mentioned collars or hubs *d*, as indicated in Fig. 3.

The apparatus can be employed as a condenser when operated under a vacuum, or as a cooler to reduce the temperature of liquid under a vacuum.

Having thus described the nature of the 110 said invention and the best means I know of carrying the same into practical effect, I claim:—

1. In apparatus of the kind referred to for treating air or gas with liquid or for 115 cooling oil or other liquid with air, the combination of a closed chamber to contain the liquid, a horizontal rotating shaft, a wheel-like member formed substantially of expanded metal provided with openings and having 120 the strips of metal between said openings inclined to the face of said member being partly submerged in the liquid and fixed to the shaft, and a fan arranged at one end of the chamber for circulating the air or gas. 125

2. In apparatus of the kind referred to for treating air or gas with liquid or for cooling oil or other liquid with air, the combination of a closed chamber to contain the liquid, a horizontal rotating shaft, a wheel- 130

like member comprising a plurality of disks of expanded metal provided with openings, the strips of metal between the openings in each of said disks being inclined to the 5 face of the disk, said disks being spaced apart, connected together and partly submerged in the liquid, said member being operatively connected with the shaft, and a fan arranged at one end of the chamber for 10 circulating the air or gas.

3. In apparatus of the kind referred to for treating air or gas with liquid or for cooling oil or other liquid with air, the combination of a horizontal rotating shaft, a 15 plurality of wheel-like members spaced apart, operatively connected with the shaft, and partly submerged in the liquid, said members each comprising a disk of expanded metal provided with openings and having 20 the strips of metal between said openings inclined to the face of the disk.

4. In apparatus of the kind referred to for treating air or gas with liquid or for cooling oil or other liquid with air, the combination of a horizontal rotating shaft, a 25 plurality of wheel-like members spaced

apart and operatively connected with the shaft, said members each comprising a plurality of disks of expanded metal, each of said disks being provided with openings and 30 having the strips of metal between said openings inclined to the face of the disk, the disks which comprise each wheel-like member being partly spaced apart, connected together and partly submerged in the 35 liquid.

5. In an apparatus of the character described, a chamber having a lower portion adapted to contain liquid, and an upright disk of expanded metal provided with openings and having the strips of metal between said openings inclined to the face of said disk, said disk being rotatably mounted in said chamber with its lower portion in said liquid. 40

In testimony whereof I have signed my name to this specification in the presence of two subscribing witnesses.

ALFRED BUTTERWORTH CLEWORTH.
